UNITED STATES PATENT OFFICE.

BENJAMIN CERUTTI OF HABANA, CUBA.

COMPOSITE BUILDING STRUCTURE.

No. 873,504.

Specification of Letters Patent.

Patented Dec. 10, 1907.

Application filed February 5, 1907. Serial No. 359,167.

To all whom it may concern:

Be it known that I, BENJAMIN CERUTTI, subject of the King of Italy, residing at Havana, Cuba, have invented certain new and 5 useful improvements in Composite Building Structures, of which the following is a specification.

This invention relates to composite walls, 10 ceilings and roofs for buildings, and has for its object to provide a simple and efficient structural combination and arrangement of parts from which a very light, rigid and substantial structure is attained in a convenient and economical manner.

15 With the foregoing and other objects in view, the invention consists in the novel construction, combination and arrangement of parts hereinafter more specifically described and illustrated in the accompanying drawings wherein is shown the preferred embodiment of the invention, but it is to be understood that changes, variations and modifications can be resorted to which come within the scope of the claims hereunto appended.

25 In describing the invention in detail reference is had to the accompanying drawings wherein like characters denote corresponding parts throughout the several views and in which—

30 Figure 1 is a longitudinal sectional view of a ceiling in accordance with this invention. Fig. 2 is a top plan view broken away. Fig. 3 is an enlarged longitudinal section. Fig. 4 is a detail in transverse section. Fig. 5 is a 35 perspective view of a portion of one of the supporting beams. Fig. 6 is a perspective view of one of the filling members and, Fig. 7 is a detail in longitudinal section of a modification. Fig. 8 illustrates in section a modified construction of supporting beam.

Referring to the drawings by reference characters, the wall, ceiling or roof comprises in its construction a plurality of supporting beams 1 of inverted T-shape, with the lower 45 portion 2 thereof constituting a base. The top of each of the beams 1 is formed with a plurality of openings 3 through which extend the short tie members 4 which project from each side of the body 5 of the beams.

50 The beams 1 at their ends are supported in any suitable manner (not shown), and between each pair of beams is positioned the filling blocks 6 which are of shell-like formation and constructed of concrete or other 55 suitable plastic material.

Each of the blocks 6 has embedded in the

sides thereof the metallic suspension cables 7, the ends of which project from the shoulders 8 formed by cutting away each end of the top wall of the block. Such cutting away of the 60 top wall also forms a ledge 9. The suspension cables 7 further constitute a means for reinforcing the block.

The bottom wall of each of the blocks 6 at each end thereof is also cut away to provide 65 a shoulder 10 and a ledge 11. The blocks 6 are positioned between a pair of beams 1 in close proximity to each other and with the ledge 11 mounted upon the top of the base 2 and the shoulder 10 abutting against the 70 edge of the base. When the blocks 6 are in such position the ends of the suspension cables 7 extend over the top edge of the beams. After the filling blocks are positioned in a manner as stated the projecting 75 ends of one pair of suspension cables of one block are secured to the suspension cables projecting from the end of an opposing block, as indicated at 12 and as best shown in Fig. 3. When the filling blocks are po- 80 sitioned in the manner as stated a recess is formed between the upper portion of a beam and the upper corners of the block which will be evident owing to the fact that the upper corners of each block, or rather the 85 top wall of each block, at each end is cut away in a manner as hereinbefore pointed out.

When the filling blocks are placed in position between the pair of supporting beams 90 and the suspension cables 7 connected together, a smooth, uninterrupted layer of cement, concrete or other plastic material is then placed upon the blocks as at 13 so as to completely cover them, as well as embedding 95 the upper end of the supporting beams. As the layer 13 also surrounds the ties 4 the supporting beams are further retained in position or prevented from sagging intermediate their ends.

In the construction shown in Fig. 7 an I-beam 14 is employed in lieu of the inverted T-shaped beams 1. The filling blocks 15 have not the top walls thereof cut away, consequently the suspension cables 7 project from the blocks at a point removed from the ends thereof. The projecting ends of the cables extend over and upon the head 16 of the beam 14 and are then connected together, as at 17. In other respects the construction shown in Fig. 7 is the same as that hereinbefore referred to.

Fig. 8 shows a modified construction of supporting beam. The reference character 18 denotes the body portion of the beam which is formed independent of the base, the latter being formed of a pair of angle irons 19, 20 which are secured to the body portion by suitable holdfast devices as indicated by the reference character 21. When the beams are required to support unusually heavy loads, which necessitates the beams to be of large cross section, it is advantageous to construct the beam or beams in the manner as shown in Fig. 8. Furthermore the setting up of the beams in such a manner reduces the cost thereof.

The form of ceiling, wall, or roof as hereinbefore referred to possesses not only the advantage of being simple in construction, strong, durable, conveniently set up, cheap, but is also substantially fire-proof and that, furthermore, the plastic filling blocks of shell-like formation are unusually strong owing to the employment of the metallic suspension cables which extend substantially from end to end of the sides of the blocks and constitute a reinforcement therefor.

What I claim is—

1. A composite structure comprising supporting beams of inverted T-shape, said beams near their top edges provided with a plurality of openings, flat tie members extending through the openings, filling blocks of shell-like formation interposed between a pair of beams and supported upon the base thereof, curvilinear suspension cables embedded in the filling blocks and projecting from each end thereof and further extending over the tops of the beams and with the ends of the cables which extend from one end of one block secured to the ends of the cables which project from the opposing end of another block, and a layer of plastic material extending over the top of the blocks and embedding the upper portion of the beams and projecting ends of the cables.

2. A composite structure comprising supporting beams of inverted T-shape, filling blocks arranged at each side of said beam, the blocks upon opposite sides of the beams each having the end which opposes the beam mounted upon the base of the latter, means for supporting the other end of the blocks, suspension cables embedded in each of the blocks and projecting from each end of their respective block, the ends of the cables at one end of the blocks at one side of the beam extending over the latter and connected to the ends of the cables which project from one end of the blocks upon the opposite side of the beam, and a layer of plastic material extending over the tops of the blocks and embedding the upper portion of the beam and projecting ends of the cables.

3. A composite structure comprising supporting beams, filling blocks arranged at each side of said beam, the blocks upon opposite sides of the beams each having the end which opposes the beam mounted upon the base of the latter, means for supporting the other end of the blocks, suspension cables embedded in each of the blocks and projecting from each end of their respective block, the ends of the cables at one end of the blocks at one side of the beam extending over the latter and connected to the ends of the cables which project from one end of the blocks upon the opposite side of the beam, and a layer of plastic material extending over the tops of the blocks and embedding the upper portion of the beam and projecting ends of the cables.

4. A composite structure comprising the combination with supporting beams, of plastic filling blocks of shell-like formation having each lower corner cut away to form a shoulder, said filling blocks of shell-like formation interposed between and having the shouldered portions thereof mounted upon the base of the beams, said lower face of the filling blocks when mounted upon the base of the beams flush with the lower face of the base of the beams, metallic cables extending through each of the filling blocks, projecting from both ends thereof and having the projecting ends extending over the tops of the beams, the projecting ends of the cables of the blocks upon one side of the beams connected to the projecting ends of the cables of the blocks upon the other side of the beams, and a layer of plastic material extending over the filling blocks and embedding the upper portion of the beams.

5. A composite structure comprising the combination with supporting beams, of plastic filling blocks of shell-like formation having each lower corner cut away to form a shoulder, said filling blocks of shell-like formation interposed between and having the shouldered portions thereof mounted upon the base of the beams, said lower face of the filling blocks when mounted upon the base of the beams flush with the lower face of the base of the beams, metallic cables extending through each of the filling blocks, projecting from both ends thereof and having the projecting ends extending over the tops of the beams, the projecting ends of the cables of the blocks upon one side of the beams connected to the projecting ends of the cables of the blocks upon the other side of the beams, and a layer of plastic material extending over the filling blocks and embedding the upper portion of the beams, combined with short tie members carried by the beams near the tops thereof and embedded in the plastic material.

6. A composite structure comprising the combination with supporting beams, of filling blocks abutting against each other, ar-

ranged between a pair of beams and supported by the base thereof, curvilinear suspension cables embedded in each of the blocks and extending from each end thereof, said extended ends of said cables of one set of blocks projecting over the tops of the beams and inter-twisted with the extended ends of the cables of an adjacent set of blocks, and a layer of plastic material upon the top of the filling blocks and embedding the upper portion of the beams.

7. A composite structure comprising the combination with supporting beams, of filling blocks abutting against each other, arranged between a pair of beams and supported by the base thereof, curvilinear suspension cables embedded in each of the blocks and extending from each end thereof, said extended ends of said cables of one set of blocks projecting over the tops of the beams and inter-twisted with the extended ends of the cables of an adjacent set of blocks, and a layer of plastic material upon the top of the filling blocks and embedding the upper portion of the beams,

25 combined with short flat tie members carried

by the beams near the tops thereof and embedded in the plastic material.

8. A composite structure comprising a supporting beam of inverted T-shape, filling blocks arranged at each side of said beam, the blocks upon opposite sides of said beam each having the end which opposes the beam mounted upon the base of the latter, means for supporting the other end of the blocks, suspension cables embedded in each of the blocks and extending therefrom, the extending ends of the cables of one set of blocks being secured to the extended ends of the cables of the other set of blocks, and a layer of plastic material extending over the tops of the blocks and embedding the upper portion of the beam.

In testimony whereof I have hereunto set my hand in presence of two subscribing witnesses.
